UNITED STATES PATENT OFFICE.

GEORGE F. GOULLEE, OF WELLSVILLE, MISSOURI, ASSIGNOR TO HIMSELF AND THOMAS K. SHELBY, OF WELLSVILLE, MISSOURI.

PHOTOGRAPHIC CHAIR.

No. 918,666.

Specification of Letters Patent.

Patented April 20, 1909.

Application filed May 7, 1908. Serial No. 431,458.

To all whom it may concern:

Be it known that I, GEORGE F. GOULLEE, a citizen of the United States, residing at Wellsville, in the county of Montgomery and State of Missouri, have invented a new and useful Photographic Chair, of which the following is a specification.

This invention has reference to improvements in posing chairs for photographers, and is designed more particularly to provide a chair for the posing of children and especially very young children preparatory to and during the operation of taking their photographs.

The invention comprises essentially a stand or support upon which is mounted a stem carrying a vertically adjustable seat, and at the upper end of the stem there is provided a clamp designed to encircle the body of the child so as to support the child upon the seat to prevent its falling therefrom. The clamp is so constructed as to firmly hold the child and at the same time may be concealed in the clothing or drapery of the child while the latter is seated upon the seat. The clamp comprises two curved members or arms slidable to and from each other and designed to encircle the body of the child, below the arms or at the waist line. The clamp structure is so arranged that the arms are readily clamped in place or they may be readily loosened for adjustment. The body of the clamp is so disposed as to be hidden by the body of the child and so will not become visible in the photograph.

The invention will be best understood from a consideration of the following detailed description taken in connection with the accompanying drawings forming part of this specification, in which drawings,

Figure 1, is a perspective view of the posing chair. Fig. 2 is a vertical central section through the clamp with parts shown in elevation, and Fig. 3 is a perspective view of the clamp with the parts separated.

Referring to the drawings there is shown a stand 1 supported upon legs 2, and rising centrally from this stand is a post or stem 3. This stem 3 may be a solid rod or it may be made hollow for lightness and its upper end is expanded laterally into a head 4 of substantially triangular shape and at appropriate points through this head are passages 5.

Secured to the head 4 by screws 6, one only 55 of which is shown, is a front plate 7, having a

downwardly extending portion 8, conforming in shape to the general shape of the head 4. It is through this downwardly extending portion 8 that the screws 6 pass. The front plate 7 above the extension 8 is provided with a passage 9 about midway of its length and also with end passages 10, these passages being counter-sunk at their outer ends for the reception of screws such as the screws 6.

Back of the plate 7 is a block 11 made fast to said plate by the screws passing through the holes 10, and midway of the block is a perforation 12 matching the perforation 9 in the plate 7. Rising from one edge of the block 11 is a flange 13 having two longitudinal slots 14 and 15 parallel one to the other and extending in the direction of the length of the block 11, which is also the direction of the length of the plate 7. The flange 13 is of such thickness that when the block 11 is attached to the plate 7, then there is a space between the corresponding face of the flange 13 and the rear face of the plate 7 for a purpose which will presently appear. To the rear of the block 11 is another plate 16, which may be termed a back plate, and this plate 16 corresponds in size and shape to the plate 7 and is also provided with a downwardly projecting portion 17 through which is a single perforation 18. Furthermore the plate 16 is provided with a central perforation 19 matching the perforation 9 in the front plate and the perforation 12 in the block 11.

In addition to the parts so far described there are provided two curved arms 20 and 21, each terminating at one end in a straight extension 22 on which is formed a tongue 23. The straight portions 22 of the arms are confined between the flange 13 of the block 11 and the front 7 with the tongue 23 entering the respective slots 14 and 15. It is desirable that the arms 20 and 21 be of the same horizontal plane but in order that the extensions 22 may pass each other these extensions are arranged in different horizontal planes. For this reason one of the arms, say the arm 21, is connected to the extension 22 by a short angle part 24 of such length that when the corresponding tongue 23 is in the slot 15 with the tongue 23 of the other arm in the slot 14, the two arms 20 and 21 are in the same horizontal plane. By this construction the arms may be caused to approach each other as close as necessary or be sepa- 110

rated as far as desired without the extensions 22 interfering one with the other when they move in different horizontal planes.

The back plate 16 is held to the post 3 by 5 the lowermost screw 6, so that the upper portion of the plate is free to move to a limited extent, to and from the flange 13 of the block 11, and the plate 16 is preferably made slightly elastic.

10 Passing through the hole 9 in the plate 7 and the perforation 12 in the block 11, and also through the perforation 19 in the plate 16, is a screw 24 which projects beyond the rear of the back plate 16 and there receives a 15 thumb or wing nut 25. The screw 24 and wing nut 25 constitute a means whereby the plate 16 may be made to bear against the rear faces of the tongues 23, which latter are made wide enough to extend through the 20 flange 13 and when the thumb nut 25 is screwed on to the screw 24 with sufficient force then the plate 16, engaging the tongues 23 will force the extensions 22 of the arms 20 and 21 against the front plate 7 and so clamp 25 these arms in any adjusted position desired. On loosening the thumb nut 25 the arms 21 are relieved from the clamping action of the plate 16 which will spring slightly outwardly, then the arms may be adjusted to 30 together or separated as the case may be, after which they may be again clamped in the adjusted position.

Mounted on the stem 3 is a sleeve 26 fastened to which is a bracket 27 carrying a seat 35 28 which may be fastened to the bracket by suitable bolts 29 or otherwise. The sleeve 26 is held in any position of adjustment on the stem 3 by a suitable set screw 30.

In using the posing chair the seat 28 is 40 adjusted to a suitable height to bring the arms 20 and 21 under the arms of the child whose picture is to be taken or these arms may be arranged to embrace the waist of the child when resting upon the seat 28. Before 45 the child is placed upon the seat 28 the arms 20 and 21 may be spread sufficiently far apart to permit the body of the child to be inserted between their contiguous ends. Then these arms are brought together until they closely 50 embrace the body of the child after which the arms may be locked in the adjusted position by a suitable manipulation of the thumb nut 25. The arms 20 and 21 will hold the body of the child firmly in position without 55 danger of the child slipping off of the seat 28, and the arms 20 and 21 may be concealed by the clothing of the child or by suitable drapery so as not to show in the picture.

In the practical embodiment of the invention, the parts will be suitably ornamented. 60 For instance, the arms 20 and 21 may be finished in any desired manner for ornamental purposes and the seat 28 may be furnished with cushions or drapery of any desired ornamental pattern.

By making the arms 20 and 21 slide toward or from each other they are caused to grasp the body of the child in the most advantageous manner without danger or hurting or pinching the child. At the same time large 70 clamping surfaces are provided so that the frictional engagement of the clamping surfaces with the arms is so extensive that but little force is required to be applied to the thumb nut 25 to firmly clamp the arms 20 75 and 21 in the adjusted position so that movement of the child will not disturb the adjustment of the arms when once made.

What is claimed is:

1. In a posing chair for photographers, 80 two opposed arms each having a straight section, and a clamp in which the straight sections are movable longitudinally, said clamp having a clamp screw for causing the clamp to engage both straight sections of the arms 85 simultaneously and thereby hold them in adjusted positions.

2. A posing chair for photographers having a base or support, a stem rising therefrom, a seat adjustable vertically on said stem, two curved arms each having one end formed into a straight section, and a clamp for the arms secured to the upper end of the stem and comprising a guide for the straight sections of the arms and through which said straight sections are movable longitudinally, clamp members on each side of the guide and engaging the straight sections of the arms, and a clamp screw engaging the clamp members and holding the arms thereby in adjusted positions.

3. In a posing chair for photographers, two opposed arms, each having straight sections and a tongue at one end, guides for the tongues, and clamp members on each side of the guides and respectively engaging the straight sections of the arms and the tongues to hold the arms in adjusted positions.

4. In a posing chair for photographers, two curved arms each having one end formed into a straight section with a lateral tongue, and a clamp for the arms, comprising two plates, a spacing block between the two plates and having at one edge a longitudinally slotted flange with the slots adapted to receive the tongues of the arms, and a clamp screw extending through the plates and intervening slots.

5. In a posing chair for photographers, two curved arms each having one end formed into a straight section with a lateral tongue, and a clamp for the arm comprising two plates one of which is elastic, a spacing block between the two plates and having at one edge a longitudinally slotted flange with the slots adapted to receive the tongues of the arms, and a clamp screw extending through the plates and the intervening block.

6. In a posing chair for photographers, two curved arms each having one end formed

into a straight section with a lateral tongue, a clamp for the arm comprising two plates one of which is elastic, a spacing block between the two plates and having at one edge 5 a longitudinally slotted flange with the slots adapted to receive the tongues of the arms, and a clamp screw extending through the plates and the intervening block, and a support for the clamp consisting of a stem termini-

nating in a head interposed between and fastened to the plates.

In testimony that I claim the foregoing as my own, I have hereto affixed my signature in the presence of two witnesses.

GEORGE F. GOULLEE.
